UNITED STATES PATENT OFFICE

2,433,466

AUTOMATIC PRESSURE AND TEMPERATURE
CONTROL

Robert L. Littlejohn, Los Angeles, Calif.

Application November 20, 1944, Serial No. 564,373

4 Claims. (Cl. 236—12)

1

This invention relates to hydraulic controls and more especially to an automatic pressure and temperature control for domestic use.

An object of the invention is to provide a simple, practical and inexpensive device of the character described.

Another object of the invention is to provide an efficient self-contained automatic pressure and temperature control unit adapted for ready installation in a domestic location.

A further object of the invention is to provide a control for hot and cold water intended primarily for use in homes such as in connection with bath tub and shower controls, however the invention is not necessarily limited to such specific type of use.

An additional object is to provide an efficient automatic pressure and temperature control for the water supply of a unit such as a tub or shower wherein a constant temperature of the water will be maintained at any selected temperature, and wherein the flow pressure may be likewise maintained constant, however being otherwise selected or regulated for any desired pressure within the pressure range of the system.

Other objects and advantages will appear and be brought out more fully in the following specification, reference being had to the accompanying drawings, wherein

Fig. 1 is a front elevation view of an embodiment of my invention.

Fig. 2 is a side elevation view of the same.

Referring more particularly to the drawing I show a cabinet 10, preferably of sheet metal or the like, having a cover 11, hinged thereto at 12, the cabinet being adapted to be flush mounted in a wall adjacent to and preferably above a hydraulic receptacle such as a bath tub in a house or dwelling. A hot water pipe 13 and a cold water pipe 14 run in the wall, enter cabinet 10 as through the bottom thereof, and are connected to a mixing chamber 15, an outlet pipe 16 being provided therefrom which is connected to a valved T-connection 17 from which a pipe 18 leads to a shower head, and a pipe 19 to an inlet nozzle of the tub.

Pipes 13 and 14 are each provided with shut-off valves 20 of any suitable design, the valve cylinders 21 thereof being provided with links 22 which are connected to a disc 23 mounted on a shaft 24, a suitable bearing member 25 being provided therefor within cabinet 10. A knurled operating knob 26 is mounted on shaft 24 and extends externally of the cabinet through an aperture 27 in cover 11, as shown in Fig. 2.

2

Pipe 13 is provided with a temperature control valve 28 and pipe 14 is provided with a similar temperature control valve 29. Valve 28 has a cylinder member 30 and valve 29 has a cylinder member 31, which cylinder members are provided with crank arms 32 which are interconnected by a link 33 and actuated together by a bell crank 34 pivoted at 35 on the housing of mixing chamber 15.

10 Pipe 16 is provided with an automatic pressure reduction valve 36 having a valve operating knob 37 and an indicating arm 38 which may register with a scale 39 suitably indicating pressures as from zero to eighty pounds per square inch, or 15 other indicia indicating variations in the pressure or rate of flow such as slow, medium and fast. This pressure control device 36 may be of any conventional construction, and the detailed features thereof are not thought to need detailed description herein. Knob 37 extends through an aperture 40 in cover 11.

Pipe 16 is provided with a thermostatic temperature control 41 of any suitable or selected construction having an operating lever 42 connected 25 by a link 43 to a bell crank 44 pivoted at 45 on the housing of control 41. A link 46 connects bell cranks 34 and 44, by which construction it will be apparent that the movement of temperature control operating lever 42 will actuate valve 30 cylinders 30 and 31, and, as shown in Fig. 1, as cylinder 30 moves to an opening position, cylinder 31 moves to a closing position, and vice versa. Temperature control 41 is provided with a control knob 47 which extends through an opening 48 in cover 11, and is provided with a pointer 49 movable over a scale 50 on the control, which scale may be calibrated in degrees as between 60 and 200, or other range of limits which may be preferred and selected.

40 The operation of the invention should be clear from the foregoing description. Valves 20 are normally kept closed when the mechanism is not in use. When it is desired to operate the control, the pressure control operating knob 37 is set 45 at any desired pressure as indicated by the scale 39, and temperature control selector 47 is similarly set at any selected temperature as indicated on scale 50. Thereupon valves 20 may be opened by rotating control knob 26 to the full open position, and hot water from pipe 13 and cold water 50 from pipe 14 will enter mixing chamber 15 and be mixed uniformly, and as the mixed water passes through the pressure control 36 the rate of flow and pressure will be regulated therein for any 55 given discharge restriction beyond the zone of

thermostatic control, thereby maintaining a predetermined pressure and rate of flow at the zone of thermostatic control. As the water passes through temperature control 41, actuating lever 42 will differentially set valve cylinders 30 and 31 of valves 28 and 29 so that the water being discharged from shower head pipe 18 or tub inlet pipe 19, will be maintained at the temperature selected, and also at the pressure determined by pressure control 36. Valve 17 may be provided with a pressure actuated plunger 17a of conventional type to direct the flow of water to shower pipe 18 or tub pipe 19.

Having described my invention what I claim is:

1. In an automatic pressure and temperature control apparatus, a plurality of supply pipes having valves, a mixing chamber connected to said supply pipes, a discharge pipe leading from said mixing chamber, a thermostatic control means in said discharge pipe adapted to actuate at least one of said valves, and an automatic pressure control means in said discharge pipe, said pressure control means being positioned between said mixing chamber and said thermostatic control means, thereby maintaining a predetermined pressure at the zone of thermostatic control.

2. In an apparatus for controlling the temperature and pressure of water, a pair of supply conduits, a mixing chamber, said supply conduits being connected with said mixing chamber, valve means in each of said conduits for controlling flow therethrough and into said mixing chamber, an automatic pressure control means and a thermostatic control means, a discharge conduit leading from said mixing chamber to said pressure control means and thence to said thermostatic control means, whereby said pressure control means maintains a predetermined pressure at the zone of thermostatic control, said thermostatic control means being adapted to differentially actuate said valve means, said pressure and thermostatic control means each having a manually

actuatable adjusting device provided with an indicator and a scale registrable with said indicator.

3. The combination as in claim 2, wherein the thermostatic control means differentially actuates said valves by a combination of bell cranks and levers correlating said thermostatic control means with said valves so as to close one of said valves while the other is being opened.

4. In an apparatus for controlling the temperature and pressure of water, a pair of supply conduits respectively for hot and cold water, a mixing chamber, said supply conduits being connected with said mixing chamber for conducting the hot and cold water into said chamber, valve means in each of said conduits for controlling flow therethrough and into said mixing chamber, an automatic pressure control means and a thermostatic control means, each of said means being adjustable respectively to provide predetermined pressure and temperature conditions, a discharge conduit leading from said mixing chamber to said pressure control means and thence to said thermostatic control means, whereby said pressure control means may afford a predetermined pressure at the zone of thermostatic control, said thermostatic control means being adapted to differentially actuate said valve means and thereby maintain the said predetermined temperature conditions of the discharged water mixture.

ROBERT L. LITTLEJOHN.
